Primary Examiner — Charles A Rademaker(74) *Attorney, Agent, or Firm* — Patterson Thuente Christensen Pedersen, P.A.(57) **CLAIM**

I claim the ornamental design for electrical dispenser for two component cartridges, as shown and described.

DESCRIPTION

FIG. 1 is a front perspective view of an electrical dispenser for two component cartridges showing our new design;

FIG. 2 is a rear perspective view thereof;

FIG. 3 is a side elevation thereof;

FIG. 4 is a side elevation of the side opposite that shown in FIG. 3;

FIG. 5 is a front elevation thereof;

FIG. 6 is a rear elevation thereof;

FIG. 7 is a top plan view thereof;

FIG. 8 is a bottom plan view thereof;

FIG. 9 is another front perspective view of the design shown in FIGS. 1-8 with broken lines showing environment that form no part of the claim;

FIG. 10 is a rear perspective view thereof;

FIG. 11 is a side elevation thereof;

FIG. 12 is a side elevation of the side opposite that shown in FIG. 3;

FIG. 13 is a front elevation thereof;

FIG. 14 is a rear elevation thereof;

FIG. 15 is a top plan view thereof; and,

FIG. 16 is a bottom plan view thereof.
